CLAIM

The ornamental design for an emergency light, as shown and described.

DESCRIPTION

FIG. 1 is a perspective view of an emergency light showing the new design.

FIG. 2 is a front elevation view thereof.

FIG. 3 is a rear elevation view thereof.

FIG. 4 is a top plan view thereof.

FIG. 5 is a bottom view thereof; and,

FIG. 6 is left end view, with the right end view being a mirror image thereof.
